FLYING SAUCER TOY

Edward H. Getz, R.D. 2, Tyrone, Pa. 16686

Filed July 24, 1969, Ser. No. 18,376

Term of patent 14 years

Int. Cl. D21—02

U.S. Cl. D34—15

FIG. 1

FIG. 4

FIG. 2

FIG. 3

FIGURE 1 is a perspective view of a flying saucer toy showing my new design;

FIGURE 2 is a top plan view thereof;

FIGURE 3 is a front plan view thereof; and

FIGURE 4 is a side plan view thereof.

I claim:

The ornamental design for a flying saucer toy, substantially as shown.
